UNITED STATES PATENT OFFICE.

WILLIAM L. GARRELS, OF ST. LOUIS, AND CLINTON KIMBALL, OF KIRKWOOD, MISSOURI.

VAPOR-BURNER FOR MOTOR-VEHICLES.

No. 844,511.

Specification of Letters Patent.

Patented Feb. 19, 1907.

Application filed October 24, 1900. Serial No. 34,139.

To all whom it may concern:

Be it known that we, WILLIAM L. GARRELS, a citizen of the United States, and a resident of the city of St. Louis and State of Missouri, and CLINTON KIMBALL, a citizen of the United States, and a resident of the city of Kirkwood, in the county of St. Louis and State of Missouri, have invented certain new and useful Improvements in Vapor-Burners for Motor-Vehicles, of which the following is a specification.

Our invention relates to burners for heating the boilers of motor-vehicles, and has for its principal objects to avoid smoke, odor, and noise in the combustion of the fuel in all parts and for all regulations of the burner, to minimize the danger of explosion, to minimize the danger of putting out the flame by the jolting of the vehicle or the blowing of the wind, to provide for the cleaning and replacing of all parts of the burner, to facilitate the lighting of the burner, and generally to improve and simplify the construction of a vapor-burner so as to make it satisfactorily fulfil all of the various conditions met with in a motor-vehicle.

To these ends our invention consists in the constructions and in the arrangements and combinations of parts hereinafter described and claimed.

In the accompanying drawings, which form part of this specification and wherein like symbols refer to like parts wherever they occur, Figure I is a vertical view, mainly in section, showing our device applied to a motor-vehicle. Fig. II is a vertical view showing the boiler partly in central section and partly in elevation and showing the burner in section upon the two planes indicated by the line 2 2 in Fig. IV. Fig. III is a side elevation of the burner. Fig. IV is a plan view of the burner, showing the casing thereof in section. Fig. V is a plan view of the rear portion of the vehicle, showing the outlet-openings for the products of combustion. Fig. VI is a similar view of a modification. Fig. VII is a fractional detail showing the rear end of the vehicle-body illustrated in Fig. VI, and Fig. VIII is a side elevation of the vehicle-body illustrated in Fig. VI.

Our device comprises two principal sections—namely, a main burner 1 and an auxiliary burner 2, the auxiliary burner being centrally located with reference to the

main burner and also with reference to the boiler 3 and furnishing a material portion of the heat furnished to said boiler and the heat for the vaporizer of the main burner. The auxiliary burner comprises a hollow body portion with tubular projections extending laterally therefrom, and both said body portions and said tubular extensions are provided with slits or perforations in their upper surfaces for the escape of vapor. The auxiliary burner is preferably cast in two sections, fastened together flatwise. Fitted into the body portion is a tube 4, provided with a series of small perforations in its upper portion. Said tube extends through the casing 5, which constitutes the wall of the combustion-chamber, and is open at its end. Projecting into the outer end of said casing is a nozzle 6, mounted on the end of a tube 7, which has a circular loop or bend therein and is connected, as hereinafter described, to the fuel-supply pipe 8. The circular loop constitutes the primary or initial vaporizer for the burner, and in order to coöperate therewith an annular drip-cup 9 is located directly below said loop, said drip-cup being adapted to hold sufficient oil to vaporize the hydrocarbon admitted into said loop. In order to secure the burning of the oil in the drip-cup with a blue flame, the loop is incased within an annular casing 10, whose sides are formed of wire-cloth or perforated metal. The drip-cup constitutes the bottom of this casing, and the top of the casing is imperforate. The side of the casing is provided with a hole to permit the insertion of a match or other igniter, and this hole is covered by a door 11 of wire-cloth or perforated metal. A pipe 12, communicating, as hereinafter described, with the main supply-pipe, passes through the casing and terminates above the drip-cup therein. This branch pipe 12 is provided with a valve 13, adapted to be manipulated by hand.

The main burner comprises a hollow body portion 14, extending diametrically beneath the boiler. The middle part of this main portion is bifurcated, so as to make an opening therein of proper size and shape to inclose the auxiliary burner. The body portion has a series of hollow lugs or bosses formed on its opposite sides. These bosses are screw-threaded, and into each of them is screwed a tube 15, closed at its end and provided with

slits or perforations communicating with the hollow interior thereof. The several tubes are arranged parallel to one another and are of such length as to conform to the periphery 5 of the boiler. The body portion of the main burner has a tube 16 connected thereto at one end and extending through the casing and open to the atmosphere at its outer end. Into this outer end projects a nozzle 17 on the 10 end of a pipe 18, which is connected through two valves 19 20, hereinafter described, to a pipe 21, which extends into the main combustion-chamber above said burner and communicates with another pipe 22 above the 15 middle portion of the burner. This last-mentioned pipe constitutes a portion of the principal vaporizer of our burner and extends entirely across the burner and projects at each end through the wall 5 of the combustion- 20 chamber and at each end is provided with a cap 23, which is screw-threaded thereon, so as to be removable at pleasure. This last-mentioned pipe communicates, through a union joint 24 located outside of the combustion-chamber, with a second pipe 25, which like- 25 wise extends entirely across the burner and is provided at each end outside of the combustion-chamber with a removable cap 26. This last-mentioned pipe 25 also constitutes part 30 of the principal vaporizer and connects through a union 27 with the main supply-pipe 8 at the end opposite that of its connection to pipe 22. On the end of the vaporizer-pipe 22 is connected a pipe 28. This pipe 28 35 is preferably made as a casting provided with three valves and adapted for connection to three pipes by union-joints. One of these pipes is the pipe 12, which feeds the drip-cup, and the valve controlling the admission thereto is the valve 13, hereinbefore mentioned. The second pipe connected to said casting is the pipe 7, constituting the initial vaporizer, and this pipe is controlled by the valve 29, mounted on the casting. The pipe 40 45 30, which preferably forms part of this casting, has a nozzle 31 on its end, which nozzle projects slightly inside of the mixing-tube 4 of the auxiliary burner. This pipe 30 is controlled by a needle-valve 32. The several 50 pipes hereinbefore mentioned constitute a single burner system and are controlled by the valves, as hereinafter more fully described. The main supply-pipe connects the fuel tank or tanks 33 directly to the pipe 25 55 and the pipe 22, together constituting the principal vaporizer, and this principal vaporizer communicates, through the pipe 30 and the nozzle thereon, with the mixing-tube of the auxiliary burner. The principal vaporizer 60 is likewise connected by the pipe 21 through the two valves 20 and 19 and the pipe 18 with the mixing tube or chamber 16 of the main burner. It is thus noted that each of the burner-sections is provided with 65 an injector connected to a vaporizer com-

mon to both, the injector being placed at substantially ninety degrees apart. The stem of the valve 19 is connected to an automatic valve-controller 34, comprising a diaphragm inclosed in a chamber which communicates, 70 through a pipe 35, with the inside of the boiler. This diaphragm is arranged in any usual manner so as to be distended by the boiler-pressure acting against the constant resistance of a counteracting spring tending 75 to open said valve. The second valve 20 in said pipe has its stem 36 prolonged so as to be within convenient reach for manipulation. The admission of fuel to the principal burner is thus cut off automatically whenever the 80 boiler-pressure exceeds a predetermined limit.

The entire burner is inclosed within a casing whose bottom preferably consists of wire-cloth or perforated metal 37, so as to allow free access of air therethrough. The burner 85 is located immediately below the boiler, whose tubes 38 are arranged vertically and open at the bottom into the combustion-chamber of the burner and open at the top into a breeching 39, which constitutes the 90 outlet-flues for the products of combustion. These flues are arranged horizontally in the top of the end portion of the vehicle-body and open upwardly at their ends. Said flues may extend beyond the sides of the vehicle, 95 as illustrated in Figs. 6, 7, and 8. The said openings are provided with wire-gauze 40 or perforated metal, which serves various purposes—namely, in connection with the screens of the burner-casings it constitutes a 100 safety device for confining the flame in case liquid fuel should accidentally get inside of the combustion-chamber and there ignite. It also by reason of its horizontal position serves to prevent the admission of air-currents into the flue. In this respect it is 105 supplemented by deflector-plates 41, arranged as indicated in Fig. 8, namely: Said plates are arranged substantially parallel with the end of the vehicle-body and inclined downwardly and rearwardly from the screens of said openings, and by reason of their inclination tend to deflect upwardly any wind from the rear blowing through such screens. By this arrangement said plates offer slight 110 resistance to the escape of the products of combustion, but constitute considerable protection against gusts of wind. The two horizontal flues are arranged in alignment with each other and with the deflective 115 plates, so that in case the wind entering one opening should pass the baffle-plates it must move toward the other opening. As an additional precaution against the wind a screen 42, as shown in Fig. 6, of wire-cloth or perforated metal may be placed across the breeching where its central portion opens into the lateral flues.

The operation of the device is as follows: One or both of the tanks 33 are filled with 120

liquid fuel. The tanks are then closed and communication is established between said tanks and a compressed-air tank 55. In order to start the fire, the valve 13 in the pipe 5 opening above the drip-cup is manipulated to fill the drip-cup with liquid fuel and is then closed. The liquid fuel in said drip-cup is then ignited, and by reason of the perforated or reticulated casing surrounding it 10 said fuel burns with a blue flame and without smoke. The heat from such flame heats the loop of the primary or initial vaporizer, and when such vaporizer is sufficiently hot the valve 29 is opened to admit liquid fuel into 15 said vaporizer. The fuel thus admitted is immediately vaporized and is injected through the nozzle 6 at the end of the vaporizer-pipe into the mixing-tube 4 or chamber of the auxiliary burner. The current of 20 vapor thus formed draws in air from the atmosphere into the mixing-chamber, and the mixed vapor and air issue through the slits in the top of said mixing-chamber and the auxiliary burner into the combustion-chamber. 25 The location of the mixing-tube of the auxiliary burner is close enough to the initial vaporizer to insure that the flame from the oil in the drip-cup will ignite the vapor escaping from the slits in the mixing-tube 4. The 30 slits in the mixing-tube constitute a train leading to the body of the auxiliary burner, whereby the fire from the drip-cup is carried directly to the auxiliary burner. The auxiliary burner may also be lighted by inserting 35 a light through a hole provided for the purpose in the wall of the combustion-chamber close to the mixing-tube 4. This hole has a cover 56, of mica or wire-gauze or other material, which will permit observation therethrough 40 of the interior of the combustion-chamber. After the auxiliary burner has been in operation long enough to heat the pipes constituting the principal vaporizer the valve 32 is opened, whereby the fuel vaporized in the 45 principal vaporizer issues from the nozzle and is injected into the mixing-tube of the auxiliary burner. The valve 29 is then closed to cut off the supply of fuel to the initial vaporizer. The valve 20 is then 50 opened to admit vapor from the principal vaporizer through the nozzle 17 into the mixing-tube 16 of the main burner, where it is mixed with air, and then issues from the slits in the top of the burner into the combustion-chamber, where it is ignited by the 55 flame of the auxiliary burner. In addition to the air admitted through the mixing-tubes there is likewise a draft of air up through the bottom of the casing on opposite sides of 60 the respective burner slits or jets, whereby the fuel is completely and properly consumed. The screen 37 on the bottom serves to prevent violent fluctuations of the draft, to which the burner would otherwise be liable 65 by reason of its exposure to the wind. The

products of combustion pass up through the tubes of the boiler into the breeching 39 and thence through the horizontal flues and out through the screened openings in the top of the vehicle-body. As hereinbefore described, the arrangement of these flues and the outlet-openings and screens therefor is such as to minimize the fluctuations of the draft and to maintain a steady consumption of fuel. 70

When the pressure in the boiler rises to a predetermined limit, it distends the diaphragm of the automatic valve-controller 34, whereby the valve 19 is automatically closed, and the supply of vapor to the main burner 80 is thereby cut off. In like manner when the pressure in the boiler falls the valve is automatically opened to admit vapor to the main burner, where it is ignited, as before described. The needle-valve 32, controlling the supply 85 of vapor to the auxiliary burner, is so adjusted as to furnish an amount of heat equal to the heat radiated from the boiler after the main burner is shut down. The proper adjustment for this purpose is ascertained by 90 experiment, and a pointer or indicator 57 is mounted on the valve-stem in position to register with any suitable mark or to abut against any suitable stop provided for the purpose. Thus our device gives a minimum 95 flame, which will not cause the steam-pressure to gradually rise and the safety-valve to blow when no steam is drawn from the boiler for some time. So, too, the said minimum flame is less likely to be jolted out 100 than if it were spread over the entire burner. By reason of its central location the heat from the auxiliary burner causes the expansion of the boiler to be distributed symmetrically, and thereby eliminates undesirable 105 strains in the boiler. In order to put out the fire in case the water in the boiler becomes so low as to expose the boiler to danger of being overheated, we provide the following device: A sleeve 58 is fastened in the center of the 110 lower tube-sheet and projects into the lower portion of the boiler and has an annular flange on the inside of its upper end. Extending upwardly through said sleeve is a second tubular sleeve 59, which has a shoulder adapted to abut against the lower end of 115 said annular flange. This last-mentioned sleeve projects below the lower tube-sheet and has its lower end formed for the engagement of a wrench. The upper end portion of 120 the bore of this sleeve has a seat formed therein, and on said seat rests a plug 60 of tin or other fusible material. Above the top of said plug said sleeve 59 is provided with one or more holes 61, opening into the water-space of the boiler. The upper end of said sleeve 59 is screw-threaded and is screwed into the lower threaded end of a tube 62, which is fastened to the upper tube-sheet 125 and opens at its upper end into the steam- 130

4 pipe 63. This tube has perforations 64 near the upper portion thereof for the admission of steam from the boiler and is otherwise equipped to constitute a steam-separator 65. 5 The operation of this construction is as follows: So long as the water covers the fusible plug 60 said plug remains in place and closes the bore of the inner sleeve. When, however, the water-level falls so low as to uncover 10 the plug 60 said plug fuses and is blown by the steam out through the bore of the sleeve 59, thereby leaving a clear passage for the steam directly from the boiler through said sleeve 59 into the combustion-chamber. 15 The steam escapes through said sleeve 59 into the combustion-chamber and smothers the flame of the burner. By locating the fusible plug centrally above the bottom of the boiler said plug will be uncovered by the 20 water when low, so that the plug will fuse and protect the boiler before any portion thereof can be overheated as well when the vehicle is tilted as when it is horizontal. For use in case of such an accident or any other 25 emergency a valve 66 is provided in the fuel-supply pipe 8 in position to be within easy reach of the driver while occupying his seat. For this purpose the supply-pipe is preferably provided with a loop 67, extending up 30 close to the side of the vehicle. By screwing the plug-holder 59 into the tube 62 they, together with the sleeve 58, constitute a strong stay for the boiler in a place where it would otherwise be weak. 35 It is noted that in the burner system hereinbefore described the vapor is fed to the auxiliary burner during all the time of the operation of the system except the initial lighting. For this reason the two valves 29 40 and 32, which control the supply of vapor to said auxiliary burner, are both located on a lower level than the other pipes and valves of the system, except only the pipe leading into the drip-cup. The reason for this is to avoid 45 pockets in the pipe system, wherein the vapor might condense and afterward be injected in liquid form into the combustion-chamber and ignited. By our arrangement any liquid formed by the condensation of vapor 50 in the pipe system during the operation thereof is drained to one or other of the two valves 29 and 32. It is also noted that such condensation of vapor is itself provided against by making the pipes in which it is liable to 55 condense as short as practicable. Another important advantage of our construction is that all parts are easily accessible for cleaning. Thus in order to clean the principal vaporizer it is only necessary to remove the 60 screw-caps at the ends of the vaporizer-tubes. As is usual with vapor-burners, wire-gauze or asbestos may be suitably arranged in the pipe system to prevent "blowing." This gauze, as well as other portions of the 65 system, is easily accessible for cleaning or

replacing by reason of the caps and of the different parts being connected together by union-joints.

Obviously the construction hereinbefore described admits of considerable modification without departing from our invention, and we do not wish to be limited to such construction. For instance, the initial vaporizer may be made part of the auxiliary burner and the drip-cup may be placed below said burner, the nozzle 31 and the valve 32 may be omitted, the main burner and auxiliary burner may be made of sheet metal in place of castings and tubes. So, too, other designs or types of boiler may be used in place of the one shown, which is a tubular boiler having a copper-lined seamless steel shell. The plug-holder 59 may be provided with lateral perforations for the escape of steam and be closed at the bottom, so as to trap the fused metal. Obviously, also, the construction of the main burner-section may be changed considerably, so long as it is provided with air-openings or passage-ways therethrough in position to supply air to opposite sides of the burner slits or jets.

What we claim is—

1. A vapor-burner comprising a burner-section having a tube perforated for the escape of vapor, an initial vaporizer and igniting device comprising a retort communicating with the source of fuel-supply, and having a nozzle connected to said tube, a drip-cup below said retort, and a casing for said burner and said retort, the inlet of said tube being located close to the initial vaporizer, substantially as described.

2. A burner comprising a main-burner section and an auxiliary-burner section and a casing therefor, said auxiliary-burner section having a mixing-tube extending through said casing and being perforated throughout the portion thereof inside of said casing, and an opening in said casing close to said mixing-tube, substantially as described.

3. A vapor-burner comprising a burner-section, a casing therefor, and a vaporizer for said burner, and an initial vaporizer comprising a retort connected to the source of fuel-supply, a drip-cup below said retort, and an annular casing of open-work or perforated metal for said retort, the casing of said initial vaporizer being arranged to provide for lighting the contents of said drip-cup, and said annular casing having an opening communicating with the interior of the burner-casing, whereby the flame from the drip-cup will ignite the vapor from said burner, substantially as described.

4. A vapor-burner comprising a burner-section, a casing therefor, and a vaporizer for said burner, and an initial vaporizer comprising a retort connected to the source of fuel-supply, a drip-cup below said retort, and an annular casing of open-work or perforated

metal for said retort, said annular casing having an opening therein to permit the lighting of the contents of the drip-cup, and having an opening communicating with the interior of the burner-casing, whereby the flame from the drip-cup will ignite the vapor from said burner, substantially as described.

5. A vapor-burner comprising a main-burner section and an auxiliary-burner section, said main-burner section, consisting of a body portion having jet-tubes extending

laterally therefrom, and said auxiliary-burner section being within the periphery of the main-burner section and having its mixing-tube located between the jet-tubes 15 of the main-burner section, substantially as described.
